UNITED STATES PATENT OFFICE.

MILTON E. BERTRAM, OF CLEVELAND, OHIO.

VALVE MECHANISM FOR INTERNAL-COMBUSTION ENGINES.

1,128,935.

Specification of Letters Patent

Patented Feb. 16, 1915.

Application filed December 18, 1911. Serial No. 696,560.

To all whom it may concern:

Be it known that I, MILTON E. BERTRAM, a citizen of the United States of America, residing at Cleveland, in the county of 5 Cuyahoga and State of Ohio, have invented certain new and useful Improvements in Valve Mechanism for Internal-Combustion Engines; and I hereby declare the following to be a full, clear, and exact description of 10 the invention, such as will enable others skilled in the art to which it pertains to make and use the same.

This invention relates to improvements in valve-mechanism for internal combustion engines, and more especially to valve-mechanism comprising a single rotary valve for controlling the supply of fuel to and the exhaust from the explosion-chamber of an engine-cylinder at a point in front of the 20 face of the piston in the cylinder during the suction stroke and exhausting stroke respectively of said piston and through one and the same cylinder-port formed in a wall of said chamber.

25 One object of this invention is to provide a simple, durable and reliable combined fuel-supply-controlling and exhaust-controlling rotary valve for a four-cycle internal combustion engine in which the piston 30 within the aforesaid cylinder successively makes its suction stroke, fuel-compressing stroke, power-imparting stroke and exhausting stroke.

Another object is to provide a valve- 35 casing having an interior chamber connected with said cylinder-port and containing a combined fuel-supply-controlling and exhaust-controlling valve having two ports which are arranged to establish communication between said cylinder-port and the fuel-supply passageway and an exhaust-passageway respectively of the valve-casing during the suction-stroke and exhausting stroke respectively of the aforesaid piston.

45 Another object is to place or arrange the exhaust-port of the valve to permit the formation of the exhaust-passageway of the valve with facility, to prevent carrying of lubricant through said exhaust-port from 50 between the valve and valve-casing, to reduce the heat transmitted from said exhaust-port to the valve and valve-casing to a minimum, and to avoid interference with the capacity of a cooling chamber formed 55 circumferentially of the valve-casing, and to utilize the exhaust through the valve in

heating the fuel supplied to the supply-port of the valve.

Another object is to arrange or place the supply-port of the valve to permit the supply of fuel to said supply-port at the lower end of the valve, to utilize the fuel supplied to said supply-port in cooling the valve and valve-casing, and more especially the exhaust-port of the valve, and to prevent carrying of lubricant through said supply-port from between the valve and valve-casing.

Another object is to render the valve accessible and readily removable for renewal, replacement or repairs should such renewal, replacement or repairs become necessary.

Another object is to render the valve suitable for use as a combined fuel-supply controlling and exhaust-controlling valve for two cylinders in common of a four-cycle internal combustion engine having more than one cylinder in which a piston successively makes its suction stroke, fuel-compressing stroke, power-imparting stroke, and exhausting stroke.

With these objects in view, and to the end of attaining any other advantage herein-after appearing, this invention consists in 55 certain structural features, and combinations and arrangement of parts, hereinafter described, pointed out in the claims, and illustrated in the accompanying drawings.

In said drawings, Figure 1 is an elevation, 90 largely in central vertical section, of an internal combustion engine, comprising two engine-cylinders and provided with valve-mechanism embodying my invention. Portions are broken away in Fig. 1 to more 95 clearly show the construction. Fig. 2 is a horizontal section taken along the line 2—2, Fig. 1, looking downwardly and drawn on a larger scale than Fig. 1. Fig. 3 is a section on line 3—3, Fig. 1, looking in the direction indicated by the arrow. Fig. 4 is a horizontal section on line 4—4, Fig. 1, looking downwardly. Figs. 5, 6 and 7 are sections taken transversely through the valve, and Figs. 4, 5, 6 and 7 illustrate said valve 100 in different positions.

Said drawings illustrate a four-cycle internal combustion engine comprising two vertically arranged interiorly chambered cylinders A and B. Said cylinders are arranged side by side, as shown in Figs. 3 and 4. Within each cylinder is a piston B

adapted to reciprocate endwise of the cylinder.

C indicates the explosion-chamber formed in each cylinder at and in front of the face of the piston in said cylinder, and D (see Fig. 3), represents an externally screw-threaded head which is screwed into said cylinder in front of the piston and forms the piston-facing wall of said explosion-chamber. The head D is provided in the usual manner with a spark-plug d, but spark-plugs or electrical devices employed for the production of electric sparks in explosion-chambers of internal combustion engines at the required time to ignite and explode any explosive fluid or fuel supplied to the said chambers are too well known in the art to require illustration and description in this specification.

20 The cylinders A and R are provided externally of the piston-containing chambers of said cylinders and out of communication with said cylinders with a cooling chamber 10 which extends longitudinally and circumferentially of said piston-containing chambers and may be supplied with cooling fluid (not shown) such, for instance, as water through a suitably valved water-supply-pipe 12 which (see Fig. 1) leads to and 30 communicates with the cooling chamber 10 at the upper end of the chamber. A suitably valved drain-pipe 13 (see Fig. 1) communicates with and leads from said cooling chamber at the lower end of the chamber.

35 The piston B in each cylinder is operatively connected in the usual manner (see Figs. 1 and 3) by a pitman b with a crank e of a horizontally arranged suitably supported crank-shaft E which is known as the engine-shaft. The shaft E is operatively provided with a pinion 15 which meshes with a spur-gear 16 operatively mounted on a suitably supported shaft F which is arranged 40 horizontally and parallel with the shaft E.

45 The shaft F is operatively provided with a bevel-gear f which meshes with a bevel-gear g operatively mounted on a suitably applied vertically arranged shaft G employed in operating a rotary valve I hereinafter described. The bevel-gears f and g correspond in diameter and number of teeth so that the valve-operating shaft G is driven at the same speed as the horizontal shaft F, but the spur-gear 16 has twice the number of 50 teeth possessed by the pinion 15 and is consequently again as large diametrically as said pinion so that the shaft F is driven to make one complete rotation during two complete rotations of the engine-shaft E, and

60 consequently the valve-operating shaft G is driven twice as slowly as the engine-shaft. The valve-operating shaft G is arranged externally of the cylinders of the engine and extends upwardly into a valve-casing 17 which (see Figs. 1 and 4) is arranged at one

side of the upper end-portions of the cylinders A and R,—that is, at one side of the explosion-chambers C in said cylinders. The valve-casing 17 is shown integral with said cylinders and provided interiorly with an upwardly flaring circular chamber 18 which is therefore arranged at one side and externally of said cylinders. The chamber 18 flares therefore in the direction in which the pistons in the cylinders face, and the upwardly flaring wall 20 of said chamber extends circumferentially of and affords lateral bearing to the correspondingly downwardly tapering vertically arranged rotary valve I. Said valve I is provided interiorly with a fuel-supply-port 21 and an exhaust-port 31, and each cylinder of the engine is provided at its upper end with a port a which connects the valve-containing chamber 18 with the explosion-chamber C of said cylinder. 85 The port a of each cylinder is arranged in the main forward of the face of the piston in said cylinder in any position of said piston and continuously communicates therefore with the explosion chamber of said cylinder, 90 and said port is employed in conducting the explosive and combustible mixture or fluid or fuel to said chamber during the suction stroke of said piston and in exhausting said chamber during the exhausting stroke of 95 said piston. The valve-casing 17 projects somewhat above the cylinder so that the upper portion of the valve I is arranged somewhat above the explosion-chambers of said cylinders and extends preferably about as 100 much above as below the cylinder-ports a. The valve-casing 17 extends a suitable distance below the valve I and is provided under the valve (see Fig. 1) with a fuel-supply-port 22 which communicates at one side 105 of the valve-casing and below the valve with a fuel-supply-pipe 23 which is applied to the valve-casing in any approved manner. The port 22 and the pipe 23 form the supply-passageway of the valve-casing. The 110 supply-port 21 of the valve is in communication at the lower end of the valve with the supply-port 22 of the valve-casing. The valve I is operatively connected, as will hereinafter appear with the valve-operating 115 shaft G which extends upwardly (see Fig. 1) through a stuffing-box H with which the bottom of the valve-casing is provided into and through the supply-port 22 of the valve-casing and upwardly into the supply-port 120 21 of the valve and into a sleeve K which is loosely mounted within said ports on the upper end-portion of said shaft. Said sleeve is therefore shiftable upwardly endwise and independently of the shaft G. The 125 valve is attached to said sleeve which is preferably provided at its upper end and externally with laterally and outwardly projecting arms k which are arranged within the supply-port 21 of the valve and spaced 130

circumferentially of the shaft G, and the valve is provided internally with lugs 24 arranged within said supply-port and resting on said arms of the sleeve and secured removably by screws J to said arms. It will be observed therefore that the shaft G is arranged at the lower end of the valve and coincidently with the axis of the valve, and operative connection between the sleeve K and said shaft is effected by a spiral spring L which is coiled around said sleeve and hooked at its lower end (see Figs. 1 and 2) onto a pin m with which said shaft is provided and hooked at its upper end (see Fig. 1) onto a pin n with which the sleeve is provided. Said spring forms such a yielding operative connection between the said sleeve and the shaft G, and consequently between said shaft and the valve, as will permit a limited rotation of said valve and said shaft independently of each other.

The sleeve-embraced portion of the shaft G is provided (see Figs. 1 and 2) with laterally projecting pins P which are spaced circumferentially of the shaft and engage slots 25 formed in the sleeve K. The shaft G is rotated in the direction indicated by the arrow placed thereon in Fig. 1. The slots 25 are of course spaced circumferentially of the sleeve K and extend from the lower end of the sleeve upwardly a suitable distance and opposite to the direction in which said shaft is rotated, and the pins P are spaced downwardly from the upper ends of said slots.

Normally the valve is seated and has bearing on the upwardly flaring surrounding wall of the chamber 18 of the valve-casing and the spring L is wound up far enough to place it under sufficient tension to cause said spring, when the engine and consequently the shaft G are at rest, to tend to rotate the valve independently of said shaft in the direction in which said shaft is rotated during the operation of the engine, so that the slots 25 shall have those side walls thereof which face in the direction in which the valve is rotated always in pressing contact with the pins P and coöperating with said pins in holding the valve to its seat formed by the valve-surrounding wall of the valve-containing chamber 18 and in preventing rotation of the valve by the spring in said direction independently of the resting shaft G. As long as there is no tendency of the valve to stick to said wall during the operation of the engine the valve rotates freely with the rotation of the shaft G through the medium of the spring, but as soon as the valve from any cause begins to stick to said wall the slots 25 will have the side walls thereof which face opposite to the direction in which the valve is rotated during the operation of the engine coöperate with the pins P of the shaft G in lifting the valve

independently of said shaft and thereby at once loosen the valve relative to said wall and render the valve free to rotate with said shaft and permit the valve to be rotated in unison with said shaft by the spring L. A head Q (see Fig. 1) is arranged above and opposite the upper end of the valve and removably secured in place in any approved manner. The head Q forms the upper end wall of the valve-containing chamber 18 of the valve-casing and is larger diametrically than the upper and diametrically larger end of the valve. The valve terminates at its upper end a suitable distance below the head Q to form a space between said head and said valve to permit of a limited lifting of the valve when the valve begins to stick to the surrounding wall of the chamber of the valve-casing. The head Q is provided centrally with an opening 32 which registers with an exhaust-pipe 33 arranged above and suitably attached to and extending upwardly from said head. The opening 32 and pipe 33 form the exhaust-passageway of the valve-casing.

The supply-port 21 of the valve has its discharging end 26 arranged at one side of the valve and in position to register at the proper time with the port a of each cylinder of the engine during the rotation of the valve and extends from said side of the valve not only into the central portion of the valve and downwardly around the sleeve K and spring L to the lower end of the valve where it communicates continuously with the supply-passageway 22 and 23 of the valve-casing but is enlarged upwardly and extends around but of course externally of the exhaust-port 31, as at 27, Fig. 1, so that said supply-port of the valve and the fluid fuel received by and passing through said valve during the operation of the engine materially participate in preventing overheating of the valve and valve-casing. The provision of the valve with a supply-port which has its receiving end at the lower extremity of the valve so as to permit the formation of the supply-passageway of the valve-casing below the valve is desirable because, first, this location of said supply-passageway renders said passageway capable of being conveniently connected to a carbureter (not shown) and reduces the cost and weight of the connection between said carbureter and the valve-casing to a minimum; second, the cold fuel coming into the valve at the lower end of the valve surrounds the valve-operating shaft G and keeps said shaft and the operative connection between said shaft and the valve in a cool condition and materially participates in preventing overheating of the moving parts of the engine, and, third, the passage of said fuel upwardly into the valve from the bottom of the valve enables said fuel to strike

the exhaust-port-forming portion of the valve where the exhaust-port turns upwardly and is mostly highly heated, and by the relative arrangement of the parts as 5 illustrated and hereinbefore described said fuel can circulate or pass around the exhaust-port and beneficially cools the exhaust-port while being beneficially influenced by the heat received thereby from the exhaust 10 port.

The exhaust-port 31 of the valve has its fluid-receiving end arranged at one side of the valve and in position to register at the proper time with the cylinder-port *a* of each cylinder of the engine during the rotation of the valve and extends from said side of the valve laterally and upwardly to a point centrally of the upper end of the valve and there communicates with the exhaust- 15 passageway of the valve-casing and consequently has its upper and fluid-discharging end arranged to discharge upwardly into and continually in communication with said exhaust-passageway of the valve-casing. 20 Preferably the surrounding wall of the exhaust-port of the valve-casing extends into the opening 32 in the head *Q* of the valve-casing, as shown in Fig. 1. The provision of the valve with an exhaust-port which ex- 25 tends diagonally of the upper portion of the valve from one side of the valve to and centrally of the upper end of the valve so as to permit the formation of the exhaust-passageway of the valve-casing above the valve 30 is desirable because, first, this location of said exhaust-passageway is most convenient; second, said relative arrangement of said exhaust-passageway and said exhaust-port prevents any material carrying off of 35 lubricant through said exhaust-port from between the valve and the valve-casing with the products of combustion discharged through said exhaust-port during the operation of the engine, and third, by said loca- 40 tion and arrangement of said exhaust-port heat transmitted from said exhaust-port to the valve and valve-casing is reduced to a minimum, and I would here remark that by the extension of the supply-port of the 45 valve upwardly to and around the exhaust-port, as shown at 27, Fig. 1, or, in other words, by the extension of said exhaust-port, as illustrated, through the upper portion of 50 said supply-port, the exhaust-port is most 55 advantageously located for the transmission of heat from the hot products of combustion discharged through said exhaust-port during the operation of the engine to the fuel supplied to said supply-port. It will 60 be observed also that the extension of the exhaust-port upwardly through the upper portion of a downwardly tapering valve which is diametrically larger at the top than at the bottom affords more room for the 65 formation of an exhaust-port having ample

capacity and permits of the extension of the supply-port around the exhaust-port as hereinbefore described, and I would here remark that overheating of the lubricant between the valve and the valve-casing is 70 only adequately prevented by conducting the products of combustion from the cylinder upwardly through the upper portion of the valve and through the supply-port of the valve, and by this arrangement of the 75 exhaust-port of the valve heat is kept, as desired, away from the operative connection between the valve and the valve-operating shaft and away from other moving parts of the engine. 80

The arrows *x* in Figs. 4, 5, 6, and 7, indicate the direction of rotation of the valve *I*.

The relative arrangement of the pistons of the two cylinders of the engine illustrated is of course such that when the piston in the cylinder *A* is in position to begin its suction stroke,—that is, at the commencement of a cycle, the piston in the other cylinder is in position to begin its exhaust-stroke,—that is, its last movement of a cycle, and by the construction hereinbefore described it is obvious that the valve *I* is rotated continuously in one direction and at one half the speed of the engine-shaft during the rotation of the engine-shaft and is so timed relative to the operation of the pistons in the cylinders that the supply-port 21 and the exhaust-port 31 of the valve communicate with each cylinder during the suction stroke and exhausting stroke respectively of the 90 piston of said cylinder. It will be observed therefore that the discharging end 26 of the supply-port 21 and the receiving end of the exhaust-port 31 of the valve are spaced circumferentially of the valve and arranged to 95 register with the ports *a* of the cylinders *A* and *R* at the proper time during the operation of the engine; that the distance circumferentially of the valve between a point centrally between the side walls of the discharging end of said supply-port and a point centrally between the side walls of the receiving end of said exhaust-port is substantially equal to one fourth of the distance 100 around the axis of the valve at said points, 105 and the relative arrangement of the parts is such that when said supply-port is about to communicate with the cylinder *A*, as shown in Fig. 4, and the piston in said cylinder is at the commencement of a cycle,— 110 that is, in position to begin its suction-stroke,—as shown in Fig. 3, the exhaust-port 31 of the valve is out of communication with the cylinder *A* and shall have begun to communicate with the cylinder *R*, as 115 shown in Fig. 4, and the piston in the last-mentioned cylinder shall be in position to begin its exhausting-stroke,—that is, the last movement of a cycle of said piston,—as 120 shown in Figs. 1 and 3. The surrounding 125 130

wall 20 of the chamber 18 of the valve-casing has that portion thereof which separates the ports *a* of the cylinders A and R large enough in dimensions circumferentially of 5 the valve to cover the supply-port of the valve (see Fig. 5) upon the interruption of communication between said valve-port and the port *a* of the cylinder A upon the first movement of a cycle of the piston of said 10 cylinder A and preparatory to the establishment of communication between said valve-port and the port *a* of the cylinder R upon the last movement of a cycle of the piston in the last-mentioned cylinder.

15 Fig. 5 illustrates the position of the valve between the first and second movements of a cycle of the piston of the cylinder A and between the last movement of a cycle and the first movement of the next succeeding 20 cycle of the piston of the cylinder R. The discharging end 26 of the supply-port 21 of the valve and the receiving end of the exhaust-port 31 of the valve are spaced circumferentially of the valve to cause the 25 latter to obstruct communication through the port *a* of the cylinder A, or through the port *a* of the cylinder R, according as the valve is in the position illustrated in Fig. 4 or in the position shown in Fig. 5. It will 30 be observed that the valve, as shown in Fig. 5, is in position interrupting communication through the ports *a* of both cylinders A and R between the first and second movements of a cycle of the piston of the cylinder A 35 and between the last movement of a cycle and the first movement of the next succeeding cycle of the piston of the cylinder R, but of course during the movement of the valve from the position shown in Fig. 4 into 40 the position shown in Fig. 5 the supply-port 21 of the valve communicates with the port *a* of the cylinder A and the exhaust-port 31 of the valve communicates with the port *a* of the cylinder R.

45 Fig. 6 illustrates the position of the valve between the second and third movements of a cycle of the piston of the cylinder A and between the first and second movements of a cycle of the piston of the cylinder R, and 50 it will be observed that in said position the valve interrupts communication through the ports *a* of both cylinders A and R, but of course during the movement of the valve from the position shown in Fig. 5 into the 55 position shown in Fig. 6 the supply-port 21 of the valve communicates with the port *a* of the cylinder R. Fig. 7 illustrates the position of the valve between the third and last movement of a cycle of the piston of the 60 cylinder A and between the second and third movements of a cycle of the piston of the cylinder R, and it will be observed that in the position of the valve shown in Fig. 7 the exhaust-port of the valve has begun to 65 communicate with the port *a* of the cylinder

A and the valve interrupts communication through the port *a* of the cylinder R, but of course during the movement of the valve from the position shown in Fig. 6 into the position shown in Fig. 7 the exhaust-port 70 of the valve has begun to communicate with the port *a* of the cylinder A, and obviously during the movement of the valve from the position shown in Fig. 7 to the position shown in Fig. 4 the exhaust-port of the 75 valve communicates with the port *a* of the cylinder A and begins to communicate with the port *a* of the cylinder R.

The cooling chamber 10 which extends circumferentially of and between the cylinders, as shown in Fig. 4, also extends, as at 80 14, circumferentially of the valve-casing 17, as shown in Figs. 1 and 4, and I would here remark that the supply of fuel to the supply-port of the valve at the lower end of the 85 valve and the discharge of the exhaust-port of the valve at the upper end of the valve permit the formation and location of the supply-passageway and exhaust-passageway 90 of the valve-casing at the upper end and lower end respectively of the valve-casing so as to interfere as little as possible with the capacity of the extension 14 of the cooling chamber 10.

95 What I claim is:—

1. The combination, with a piston-containing cylinder of an internal combustion-engine, which cylinder has a port communicating with the interior of the cylinder and a valve-casing which has a supply-passageway and an exhaust-passageway formed at the lower end and upper end respectively of the valve-casing, of a downwardly tapering upright rotary valve arranged within the valve-casing and having a supply-port which extends upwardly from the lower and diametrically smaller end of the valve and is continuously in communication at said end with the aforesaid supply-passageway and has its outlet 110 arranged to discharge at one side of the valve into the aforesaid cylinder-port at the proper time during each complete rotation of the valve, said valve having an exhaust-port which extends laterally inwardly 115 and upwardly through the upper and diametrically larger portion of the valve from one side of the valve and is arranged to register at its lower end with the cylinder-port at the proper time during each complete rotation of the valve, said exhaust-port 120 continuously communicating at the upper and diametrically larger end of the valve with the aforesaid exhaust-passageway.

2. The combination, with a piston-containing cylinder of an internal combustion-engine, which cylinder has a port communicating with the interior of the cylinder, and a valve-casing, of a downwardly tapering upright rotary valve 125

ranged within the valve-casing and having a supply-port which is spaced downwardly from the upper and diametrically larger end of the valve and arranged to communicate with the aforesaid cylinder-port at the proper time during each complete rotation of the valve, said valve having an exhaust-port which extends through the upper and diametrically larger portion of the valve and is arranged to communicate with the cylinder-port at the proper time during each complete rotation of the valve, said exhaust-port discharging at and centrally of the top of the valve.

5. In valve-mechanism for a four-cycle internal combustion engine, the combination, with a piston-containing cylinder provided with a port communicating with the interior of the cylinder forwardly of the 20 piston in the cylinder in any position of the piston, of a valve-casing provided interiorly with an upwardly flaring circular chamber which connects at one side with said cylinder-port and having a supply-passageway 25 and an exhaust-passageway formed at the lower end and upper end respectively of the valve-casing, and an externally downwardly tapering upright rotary valve seated on the surrounding wall of said chamber, 30 which valve has a supply-port extending upwardly from the lower end of the valve and communicating with the aforesaid supply-passageway and arranged to discharge at one side of the valve into the aforesaid 35 cylinder-port during the rotation of the valve, said valve having an exhaust-port extending through the upper portion of the valve and discharging at and centrally of the upper end of the valve into the aforesaid 40 exhaust-passageway and arranged to place said cylinder-port into communication with said exhaust-passageway during the rotation of the valve.

4. The combination, with a piston-containing cylinder of an internal combustion engine, which cylinder has a port communicating with the interior of the cylinder, and a valve-casing which has a supply-passageway at its lower end and an exhaust-passageway at its upper end, of 50 a downwardly tapering upright rotary valve arranged within the valve-casing and having a supply-port which communicates at the lower and diametrically smaller end 55 of the valve with the aforesaid supply-passageway and extends upwardly from said end of the valve and has its outlet arranged to discharge at one side of the valve into the aforesaid cylinder-port at the proper time 60 during each complete rotation of the valve, said valve having an exhaust-port which communicates at one side of the valve with the cylinder-port at the proper time during each complete rotation of the valve, said valve having an exhaust-port which communicates at one side of the valve with the cylinder-port at the proper time during each complete rotation of the valve, 65

1 exhaust-port extending through the

upper and diametrically larger portion of but being out of communication with the aforesaid supply-port and communicating at the top of the valve with the aforesaid exhaust-passageway.

5. The combination, with a piston-containing cylinder of an internal-combustion engine, which cylinder has a port communicating with the interior of the cylinder, and a valve-casing which has a supply-passageway at its lower end and an exhaust-passageway at its upper end, of a downwardly tapering upright rotary valve arranged within the valve-casing and having an exhaust-port which extends through the upper portion of the valve from one side of the valve and communicates at the top of the valve with the aforesaid exhaust-passageway and is arranged to place the aforesaid cylinder-port into communication with said exhaust-passageway at the proper time during each complete rotation of the valve, 80 said valve having a supply-port which communicates at the lower end of the valve with the aforesaid supply-passageway and extends upwardly from said end of the valve and has its outlet arranged to discharge at one side of the valve into the cylinder-port at the proper time during each complete rotation of the valve, said supply-port being out of communication with the aforesaid exhaust-port but extending around said exhaust-port at a point above the cylinder-port.

6. The combination, with a piston-containing cylinder of an internal-combustion engine, which cylinder has a port communicating with the interior of the cylinder, and a valve-casing which has a supply-passageway and an exhaust-passageway formed at its lower end and upper end respectively, of a downwardly tapering upright rotary valve arranged within the valve-casing and having a supply-port which communicates at the lower end of the valve with the aforesaid supply-passageway and extends upwardly from said end of the valve and has its outlet arranged to discharge at one side of the valve into the aforesaid cylinder-port at the proper time 100 during each complete rotation of the valve, said valve having an exhaust-port which communicates at one side of the valve with the cylinder-port at the proper time during each complete rotation of the valve, said exhaust-port being out of communication with but extending substantially diagonally of and through the upper portion of the aforesaid supply-port and communicating centrally of the top of the valve with the 110 aforesaid exhaust-passageway.

7. In valve-mechanism for a four-cycle internal combustion engine, the combination, with a piston-containing cylinder provided with a port communicating with the interior

of the cylinder forwardly of the piston in the cylinder in any position of the piston, of a valve-casing provided interiorly with an upwardly flaring circular chamber which 5 connects at one side with the aforesaid cylinder-port, said valve-casing having a supply-passageway and an exhaust-passageway formed at the lower end and upper end respectively of the valve-casing, and a downwardly tapering rotary valve arranged 10 within said chamber and having a supply-port communicating at the lower end of the valve with the aforesaid supply-passageway and extending upwardly from said end of 15 the valve and arranged to discharge at one side of the valve into the aforesaid cylinder-port during the rotation of the valve, said valve also having an exhaust-port extending

from one side of the valve through the upper portion of the valve and diagonally of 20 and through the upper portion of but being out of communication with the aforesaid supply-port and discharging upwardly centrally of the top of the valve into the aforesaid exhaust-passageway and arranged to 25 place said cylinder-port into communication with said exhaust-passageway during the rotation of the valve.

In testimony whereof, I sign the foregoing specification, in the presence of two 30 witnesses.

MILTON E. BERTRAM.
